UNITED STATES PATENT OFFICE.

JOSEPH HAUSER, OF SPOKANE, WASHINGTON.

SUSPENDER ATTACHMENT.

No. 904,955.

Specification of Letters Patent.

Patented Nov. 24, 1908.

Application filed July 3, 1907. Serial No. 382,058.

To all whom it may concern:

Be it known that I, JOSEPH HAUSER, a citizen of the United States, and a resident of Spokane, in the county of Spokane and State 5 of Washington, have invented new and useful Improvements in Suspender Attachments, of which the following is a full, clear, and exact description.

This invention relates to novel attachments 10 for suspenders, which afford means for reliably securing together the ends of the looped portions of suspender bands, in a manner which will permit the release of said parts when a changed adjustment is desired, 15 whereby the suspender bands are lengthened or shortened as occasion may require.

Furthermore, the invention embodies means 20 for holding the ends of the suspender bands and suspender tabs in secured engagement with proper buttons on the waist band of trousers, and enabling an instant release of the tabs when this is desired.

The invention consists in the novel construction and combination of parts, as is 25 hereinafter described and defined in the appended claims.

Reference is to be had to the accompanying drawings forming a part of this specification, wherein similar characters of reference indicate 30 corresponding parts in all the views.

Figure 1 is a perspective view of a pair of suspenders constructed as usual, and a front view of the improved clamping attachment thereon; Fig. 2 is an enlarged, front view of 35 the tab end of a suspender band, a trousers waist band in part, and a feature of the invention on the tab end, detachably securing said tab end upon a button on the waist band; Fig. 3 is a perspective view showing a clasp 40 attachment for the tab ends of suspenders, mainly at the front thereof; Fig. 4 is a vertical transverse, sectional view of details, substantially on the line 5—5 in Fig. 3, and Fig. 5 is a perspective view showing the rear 45 of the tab and clasp, that is shown at the front in Fig. 4.

In the drawings, 10 represents a pair of suspender bands crossed and secured together near their rear ends and doubled at the 50 front ends, the bights of said doubled portions 10^a loosely engaging the transverse upper slots in coupling plates *a*, the twin slots in the latter receiving the bights of a pair of integral tabs 11, as usual.

The novel clasps with which the ends of 55 the tabs 11 are provided, each comprise the following details. A body portion for the tab end clasp is formed of plate metal, that when flat is rectangular and oblong. This plate is bent at *d*, that is the longitudinal 60 center thereof, so as to produce two similar members for the body, these members 12, 12^a, being spaced apart parallel with each other. The body having the spaced members 12, 12^a, is loosely secured on the pendent end of a 65 tab 11 by means of an oblong ring *e*, that is placed on the clasp body engaging the bight thereof, and fastened upon the extremity of the tab by lap folding the latter and securing the lapped portion on the pendent 70 tab after it has been passed through the oblong ring, as shown for one clasp and tab end in Fig. 4. The normally front side of the body piece designated by the character 12, is slotted at the transverse center from 75 the lower edge toward the bend *d*, the slot *d'* being of a width that will permit the free insertion of the neck of a trousers button *A* into this slot *d'* when the device is to be used. A safety latch plate 13 is an essential detail, 80 and as clearly shown in Figs. 2 and 3, consists of a metal plate, flat in the body and having a bent latch finger *g* at one side edge thereof, this latch finger being designed to hook upon one side edge of the slotted member 85 12. At the corner of the latch plate 13 which is opposite from the latch finger *g*, said latch plate is pivoted upon the member 12 as at *i*, and as shown the lower corner *h* on the opposite side edge of said member 12, 90 is rounded somewhat. At the upper termination of the rounded edge *h* a slight hump *h'* is formed, whereon the hook-like latch finger *g* will rest when the latch plate is 95 rocked into the position shown in Figs. 2 and 3, there being sufficient resilience in the slotted member 12 to permit the passage of the finger *g* over the hump *h'*. The upper edge of the latch plate 13 is concaved, as appears in Fig. 3, at a point opposite the slot *d'*, 100 this concaved portion of said edge engaging the neck of a button when the plate is in latched position. The other spaced member 12^a of the looped body for the trousers holding clamp is slotted transversely, as is 105 shown in Figs. 4 and 5, said slot *h* being disposed about opposite the pivot *i* and hooked finger *g*.

A locking plate or lever 14 is employed as a completing detail of the tab end clasp which has been described. This lever is formed of a flat, metallic plate having a lateral flange m formed on the normally upper edge thereof, said flange working in the slot h that it is positioned opposite, by pivoting the lever at its side edges close to the flange and at each side edge of the lever, as indicated at n in Fig. 5.

The clasps carried by ends of the tabs are preferably attached upon the rear ends of the suspender bands 10 or tabs 11^a thereon, for engagement with the edge portion of the waist band B of a pair of trousers at the buttons usually placed on the waistband for engagement with said rear ends or tabs of the suspenders.

In applying the improved clasps that are mounted upon the tabs or rear ends 11^a of the suspender bands, the latch plates are turned down away from the slots in the outer members 12 of the clasp bodies, as indicated in dotted lines in Figs. 2. The buttons A, which ordinarily are connected with the suspender bands at their rear ends, are now introduced into the slots in the body member 12, which will dispose the material of the trousers waist-band B at the buttons A between the clasp body members 12 and 12^a. Now, by swinging the latch plate 13 that is on each member 12, around so as to hook its finger g over the hump h' and then foldably adjusting the locking levers 14, the flanges m on said levers will be embedded in the material of the trousers waist-band, and firmly but detachably secure the rear ends of the suspenders upon the trousers.

As the clasps that are secured upon the pendent end portions of the tabs 11 are similar in every respect to those on the suspender rear ends or tabs 11^a, the connection of said clasps with the waist band at the front buttons on the trousers will obviously be the same as already described, and need not be repeated.

It is to be understood that the improved clasps may be employed for connecting the body of a woman's dress with the skirt if this is desired, or a body for a boy's upper garment may be detachably secured upon the nether garment, if this is preferred to the use of buttons for such a purpose.

Having thus described my invention, I

claim as new and desire to secure by Letters 55 Patent:

1. A clasp for suspender ends, comprising a plate having a slot leading out through one edge of the plate and adapted to receive the neck of a button, a latch mounted on the plate and adapted to extend across the slot of the plate, and a locking lever carried by the plate and adapted to engage the material carrying the button opposite the said button.

2. A clasp for suspender ends, comprising a U-shaped plate having in its front member a vertical slot leading out through its lower edge, a latch pivoted to the plate at one side of the slot and having locking engagement with the plate at the other side of the slot, and a locking lever carried by the rear member of the plate and adapted to engage the material carrying the button opposite said button.

3. A clasp for suspender ends, comprising a plate having a vertical slot leading out through the lower end thereof and provided with a projection on one side edge, and a latch pivoted to the plate at one side of the slot and provided with a finger at its free end for engaging the edge of the plate having the projection.

4. A clasp for suspender ends, comprising an inverted U-shaped plate having a vertical slot on one member, said slot leading out through the lower end of said member, and a latch pivoted to the member of the plate having the vertical slot and provided at its free end with a hook extending around and in locking engagement with one edge of the said member.

5. A clasp for suspender ends, comprising an inverted U-shaped plate having its members slotted, the slot of the front member being vertical and leading out through the lower end of the member, a latch pivoted to the front member and having locking engagement with the member at the other side of the slot, and a locking lever pivoted to the rear member and having a projection extending into the slot thereof.

In testimony whereof I have signed my name to this specification in the presence of two subscribing witnesses.

JOSEPH HAUSER.
